DERIVATIVES OF THE 2-(LOWER ALKYL)-3-(LOWER ALKYL)-4-PHENYL-3, OR 4-CYCLOHEXENECARBOXYLIC ACIDS

George Karmas, Bound Brook, N.J., assignor to
Ortho Pharmaceutical Corporation

No Drawing. Continuation-in-part of application Ser. No. 763,026, Sept. 26, 1968, now Patent No. 3,629,269.
This application Mar. 11, 1971, Ser. No. 123,471
Int. Cl. C07c 69/76

U.S. CL. 260—469

3 Claims

ABSTRACT OF THE DISCLOSURE

Compounds of the general formula

are disclosed wherein R'' and R''' are selected from the group consisting of lower alkyl of up to 3 carbon atoms; and R' is selected from the group consisting of secondary alkyl of from 9 to 20 carbon atoms, alkenyl of from 3 to 20 carbon atoms, 1-adamantyl, 2-adamantyl, cyclopentyl; and the dotted lines represent a double bond at either the 3- or the 4-position. These compounds are active suppressants of reproduction in low doses when administered orally or parenterally. When given in a single subcutaneous and/or oral dose, some of these compounds have long acting effects in the suppression of animal reproduction.

This application is a continuation-in-part of my application Ser. No. 763,026, filed Sept. 26, 1968, now Pat. No. 3,629,269.

The present invention relates to compounds of the general formula

wherein R'' and R''' are selected from the group consisting of lower alkyl of up to 3 carbon atoms; and R' is selected from the group consisting of secondary alkyl of from 9 to 20 carbon atoms, alkenyl of from 3 to 20 carbon atoms, 1-adamantyl, 2-adamantyl, cyclopentyl; and the dotted lines represent a double bond at either the 3- or the 4-position.

The compounds of the present invention are related to the compounds disclosed in U.S. Pat. 3,344,147 and in my copending patent applications Ser. Nos. 662,310, now Pat. No. 3,591,624; 747,075, now abandoned; 622,295, now Pat. No. 3,567,770; 723,614, now abandoned; and 728,900, now Pat. No. 3,557,129. The compounds of the present invention are active suppressants of reproduction in low doses upon oral or parenteral administration. Some of the compounds of the present invention, when given in one subcutaneous injection or in one oral dose, suppress reproduction over a long period of time.

2

These compounds are all esters of 2-(lower alkyl)-3-(lower alkyl)-4-phenylcyclohexenecarboxylic acid and analogs of the same and therefore may be prepared by the formation of the acid halide of the cyclohexenyl carboxylic acid (by means of reaction with thionyl chloride or phosphorus halides) followed by reaction with an alcohol of the formula R'OH. Alternatively, the appropriate metal salt of the cyclohexenyl acid may be reacted with a compound of the formula R'-(halide), for example with α -glyceryl monochlorohydrin, or with an alkylsulfonate of the formula R'-OSO₂R''. A further method consists of preparing the anhydride of the cyclohexenyl acid (for instance, by reacting with acetic anhydride) and condensing the product with a hydroxylic reagent of the formula R'OH.

Furthermore, the anhydride of a 4-hydroxy-4-arylcyclohexanecarboxylic acid may first be prepared after which it is condensed with the appropriate alcohol of the formula R'OH and the resultant ester subsequently dehydrated in the presence of a Lewis acid in order to prepare the corresponding cyclohexenyl carboxylic acid ester. Said dehydration step is preferably effected with hot glacial acetic acid and paratoluenesulfonic acid. This particular reaction sequence is illustrated as follows:

The present compounds may also be prepared by acid catalysed esterification between the cyclohexenyl carboxylic acid and an alcohol of the formula R'OH; transesterification, in which the R'O-group of the ester is replaced with another R'-O group under basic catalysis; or by the reaction of the cyclohexenyl carboxylic acid with a diazoalkane or an olefin. The latter two processes may be generally illustrated as follows:

In the above formulae, R_1 , R_2 , R_3 and R_4 represent hydrogen or a wide range of substituents such as alkyl, alkenyl and substituted alkyl or alkenyl.

The following examples illustrate the preparation of some of the compounds of the invention. While only one method of preparation is disclosed for each compound, it is to be understood that a number of the other methods noted above can also be utilized.

In said examples, reference to the *drying* of organic solutions implies the use of anhydrous magnesium sulfate or sodium sulfate, *evaporation* is invariably performed under vacuum (most conveniently that obtained with a waterpump aspirator), filtration is with suction, *temperatures* are degrees Centigrade, and *melting points* are corrected.

Infrared spectra (neat for oils, KBr pellets for solids) were taken on a Beckman IR-5 spectrophotometer and proton magnetic resonance (NMR) spectra on a Varian A-60 instrument. NMR spectral data are given as chemical shift values, δ , in p.p.m. The δ values given in the following examples are those assignable, where possible, to a vinyl proton on the cyclohexene ring and to the 2-methyl and 3-ethyl groups.

ESTERS FROM A SODIUM CARBOXYLATE AND A HALIDE

Example 1.— β,γ -Dihydroxypropyl 2-Methyl-3-ethyl-4-phenyl-4-cyclohexenecarboxylate

A solution of 2.0 g. of 2 - methyl - 3 - ethyl - 4 - phenyl-4-cyclohexenecarboxylic acid reported in U.S. Pat. No. 3,344,147 and 0.5 g. of sodium hydroxide in 25 ml. of methanol plus 60 ml. of dimethylformamide is evaporated to a volume of 40 ml. and to the resulting slurry is added 4 ml. of α -glyceryl monochlorohydrin. This mixture is heated at 100° for 2½ hours and then it is evaporated to remove dimethylformamide. The residue is shaken with ether and water and then the ether phase is washed twice with cold 5% sodium hydroxide and four times with water. Evaporation of the dried ether solution leaves a viscous oil which slowly crystallizes. Recrystallization from ether-hexane affords 1.30 g. of fine white flakes, m.p. 72-73°.

$\lambda\lambda_{\text{max}}$: 2.89, 5.81, 8.25, 8.48, 8.56, 11.83, 13.21, 14.20 μ (KBr)

NMR (CDCl₃): 0.80, 0.85, 0.92, 1.01; 5.65.

Calcd. for C₁₉H₂₆O₄: C, 71.67; H, 8.23. Found: C, 71.78; H, 8.17.

ESTERS FROM ACID CHLORIDE AND AN ALCOHOL

Example 2.—1-Adamantyl 2-Methyl-3-ethyl-4-phenyl-4-cyclohexenecarboxylate

A mixture of 3.0 g. of 2-methyl-3-ethyl-4-phenyl-4-cyclohexenecarboxylic acid and 15 ml. of thionyl chloride is refluxed for fifteen minutes and then the yellow solution is evaporated and the residual oil is distilled to afford 3.0 g. of the acid chloride, a mobile yellow oil which boils at 100-102°/0.02 mm. and has n_D^{23} 1.5527 and $\lambda\lambda_{\text{max}}$. 5.57, 9.98, 11.63, 12.35, 13.10-13.40, 14.28 μ (neat).

The distilled acid chloride is added to a chilled (5-10°), vigorously stirred solution of 1½ molecular equivalent of 1-hydroxyadamantane in 20 ml. of dry pyridine. This reaction mixture is stirred at 25° for 15 minutes and then heated at 90-95° for 15 minutes. Then it is cooled and 5 ml. of water is added and the mixture is stirred vigorously for 2 hours. After dilution with 150 ml. of ether, the ether phase is washed twice with cold 5% hydrochloric acid to remove pyridine, then twice with cold 5% sodium hydroxide and then the ether solution is dried and evaporated. The residual oil is developed on a column of alumina (neutral, W-1) prepared in benzene-hexane. Elution with benzene and ether affords the ester free of alcohol and carboxylic acid. A crystalline ester is recrys-

tallized from methanol, and an oily ester is distilled under high vacuum to afford the following purified product. 1-Adamantyl 2 - Methyl - 3 - ethyl - 4 - phenyl - 4 - cyclohexenecarboxylate; m.p. 94-95°.

5 $\lambda\lambda_{\text{max}}$: 5.81, 8.22, 8.49, 9.42, 10.23, 13.14, 14.20 μ (KBr).

NMR (CDCl₃): 0.77, 0.83, 0.88, 5.63.

Calcd. for C₂₆H₃₄O₂: C, 82.49; H, 9.05. Found: C, 82.32; H, 9.17.

Example 3.—Benzhydryl 2-Methyl-3-ethyl-4-phenyl-4-cyclohexenecarboxylate

This compound is prepared following the procedure of Example 2, and using benzhydrol in the place of 1-hydroxyadamantane.

The compound is a viscous yellow oil of b.pt. 190-200°/0.001 mm.;

15 $\lambda\lambda_{\text{max}}$: 5.79, 8.63, 10.07, 11.80, 13.20, 14.26 μ (neat).

NMR (CHCl₃): 0.70, 0.81, 0.89, 5.65.

Calcd. for C₂₉H₃₀O₂: C, 84.84; H, 7.37. Found: C, 85.05; H, 7.45.

Example 4.—Cyclopentyl 2-Methyl-3-ethyl-4-phenyl-4-cyclohexenecarboxylate

This compound is prepared following the procedure of Example 2, and using cyclopentanol in the place of 1-hydroxyadamantane.

Distillation (without prior chromatography) gives an oil, b.p. 125-130°/0.001 mm. This solidifies and is recrystallized from methanol to give white flakes, m.p. 58-59°. Yield: 75%.

20 $\lambda\lambda_{\text{max}}$: 5.81, 8.29, 8.64, 11.90, 13.25, 14.23 μ (KBr). Empirical Formula: C₂₁H₂₈O₂.

Anal.—Calcd.: C, 80.73; H, 9.03. Found: C, 80.81; H, 9.04.

Example 5.—Decyl 2-Methyl-3-ethyl-4-phenyl-4-cyclohexenecarboxylate

This compound is prepared following the procedure of Example 2, and using n-decyl alcohol in the place of 1-hydroxyadamantane.

Chromatography, followed by distillation (b.p. 175-180° at .001 mm.) affords the decyl ester as a very pale yellow, mobile oil.

25 $\lambda\lambda_{\text{max}}$: 5.78, 8.29, 8.60, 11.88, 13.22, 14.27 μ .

Empirical Formula: C₂₆H₄₀O₂.

Calcd.: C, 81.20; H, 10.48. Found: C, 80.78; 80.75; H, 10.29; 10.49.

Example 6.—(2-Methyl-3-ethyl-4-phenyl-4-cyclohexenyl-1) - methyl 2 - Methyl-3-ethyl-4-phenyl-4-cyclohexene-carboxylate

To a stirred solution of 2.9 g. of (2-methyl-3-ethyl-4-phenyl - 4 - cyclohexenyl - 1)methanol (prepared as described in U.S. Pat. No. 3,344,147) in 12 ml. of pyridine is added 3 g. of distilled 2-methyl-3-ethyl-4-phenyl-4-cyclohexenecarbonyl chloride (prepared as described in Example 2). This mixture is heated at 90-95° for twenty minutes and then ice and ether are added. The mixture is shaken and then separated. The ether solution is washed twice with cold dilute hydrochloric acid and then with water and dilute sodium hydroxide. The residue obtained from drying and evaporation of the ether solution is triturated with pentane and stored at 0° to afford 2.4 g. of a crystalline solid ester which is recrystallized from ether and from acetone to afford 1.65 g. of (2-methyl-3-ethyl-4 - phenyl - 4 - cyclohexenyl-1)methyl 2-methyl-3-ethyl-4-phenyl - 4 - cyclohexenecarboxylate, white granules of m.p. 153-156°.

70 $\lambda\lambda_{\text{max}}$: 5.77, 8.23, 8.43, 8.51, 9.94, 11.80, 13.14, 14.12, 14.22 μ (KBr).

Empirical Formula: C₃₂H₄₀O₂.

Calcd.: C 84.16; H, 8.83. Found: C, 84.05; H, 8.88.

Example 7.—2-Adamantyl 2-Methyl-3-ethyl-4-phenyl-4-cyclohexenecarboxylate

3.0 g. of 2 - methyl - 3-ethyl-4-phenyl-4-cyclohexene-carboxylic acid is converted to the acid chloride as described in Example 2. The distilled acid chloride is added to a solution of 2-hydroxyadamantane in 10 ml. of dry pyridine. This reaction mixture is maintained at 25° for 10 minutes and then it is heated at 90-95° for 10 minutes. Six drops of water are added and heating is continued for 5 minutes longer. After cooling, the reaction mixture is diluted with ether and then it is washed with dilute hydrochloric acid, water, and dilute potassium carbonate. Drying and evaporation of the ether solution affords a viscous yellow oil which is developed on a chromatographic column of neutral alumina. Elution with benzene-ether affords the ester as a colorless oil which slowly solidifies. This is recrystallized twice from hexane to afford 1.8 g. of 2 - adamantyl 2-methyl-3-ethyl-4-phenyl-4-cyclohexenecarboxylate, fine white prisms which melt at 83-84°. $\lambda\lambda_{\text{max}}$: 5.78, 8.25, 8.54, 9.91, 13.04, 13.23, 14.20 μ (KBr). Empirical Formula: $C_{26}H_{34}O_2$. Calcd.: C, 82.49; H, 9.05. Found: C, 82.57; H, 8.95.

Example 8.—1-Adamantylmethyl 2-Methyl-3-ethyl-4-phenyl-4-cyclohexenecarboxylate

3.0 g. of 2 - Methyl-3-ethyl-4-phenyl-4-cyclohexene-carboxylic acid is converted to the acid chloride as described in Example 2. The distilled acid chloride is then reacted with 2.0 g. of 1-adamantylmethanol in pyridine as described for Example 7. The working up and chromatography are as for the compound of Example 7 and there is thus obtained 2.8 g. of 1 - adamantylmethyl 2 - methyl-3-ethyl - 4 - phenyl-4-cyclohexenecarboxylate, a very viscous oil which is freed of solvent under high vacuum. This ester may be distilled at 180-190°/0.001 mm., but this causes partial decomposition and is not a useful method of purification.

$\lambda\lambda_{\text{max}}$: 5.79, 6.90, 8.28, 8.60, 9.90, 11.88, 13.20, 14.28 μ . Empirical Formula: $C_{27}H_{36}O_2$. Calcd.: C, 82.60; H, 9.24. Found: C, 82.87; H, 9.23.

Example 9.—Benzyl 2-Methyl-3-ethyl-4-phenyl-4-cyclohexenecarboxylate

This ester is prepared from the cyclohexenyl acid chloride and benzyl alcohol, following the procedure of Example 2. Chromatography, followed by distillation (b. pt. 170-173° at 0.001 mm.) affords the benzyl ester as a colorless oil.

$\lambda\lambda_{\text{max}}$: 5.79, 8.30, 8.63, 9.95, 11.85, 13.28, 14.30 μ . Empirical Formula: $C_{23}H_{36}O_2$.

Calcd.: C, 82.59; H, 7.84. Found: C, 82.79; H, 7.88.

Example 10.—2-Nonadecyl 2-Methyl-3-ethyl-4-phenyl-4-cyclohexenecarboxylate

This ester is prepared from the cyclohexenyl acid chloride and 2-nonadecanol, following the procedure of Example 2. Chromatography on alumina affords the crude ester free of the fatty alcohol, and distillation gives the ester as a yellow oil of b.pt. 230-235°/0.001 mm.

$\lambda\lambda_{\text{max}}$: 5.78, 8.27, 8.58, 11.87, 13.20, 14.28 μ .

Empirical Formula: $C_{35}H_{56}O_2$.

Calcd.: C, 82.29; H, 11.45. Found: C, 82.19; H, 11.71.

Example 11.—2-Methyl-2-butenyl 2-Methyl-3-ethyl-4-phenyl-3-cyclohexenecarboxylate

This ester is prepared from the cyclohexenyl acid chloride and 2,3-dimethylallyl alcohol, following the procedure of Example 2. Chromatography on alumina affords a crude ester and distillation gives the desired ester as a colorless oil of b. pt. 125-130° at .001 mm.

$\lambda\lambda_{\text{max}}$: 5.78, 8.64, 10.00, 12.04, 13.13, 14.27 μ .

Empirical Formula: $C_{21}H_{28}O_2$.

Calcd.: C, 80.73; H, 9.03. Found: C, 80.57; H, 8.89.

Example 12.—2-Methyl-2-butenyl 2-Methyl-3-ethyl-4-phenyl-4-cyclohexenecarboxylate

This ester is prepared from the Δ^4 -cyclohexenyl acid chloride and 2,3-dimethylallyl alcohol, following the procedure of Example 2. Chromatography on alumina affords crude ester and distillation gives the desired ester as a colorless oil of b. pt. 135-140°/.001 mm.

$\lambda\lambda_{\text{max}}$: 5.78, 8.29, 8.63, 10.04, 11.89, 12.06, 13.27, 14.27 μ .

Empirical Formula: $C_{21}H_{28}O_2$ =312.4.

Anal.—Calcd.: C, 80.73; H, 9.03. Found: C, 81.06; H, 9.02.

Example 13.—2-Furylmethyl 2-Methyl-3-ethyl-4-phenyl-4-cyclohexenecarboxylate

This ester is prepared from the cyclohexenyl acid chloride and furfuryl alcohol, following the procedure of Example 2. Chromatography affords a crystalline ester which is purified by recrystallization from ether to afford the 1-furylmethyl ester, white prisms of m.p. 83-84°.

$\lambda\lambda_{\text{max}}$: 5.80, 8.29, 8.56, 8.62, 11.9-12.0, 13.11, 13.41, 14.20 μ . (KBr).

Empirical Formula: $C_{21}H_{24}O_3$.

Calcd.: C, 77.75; H, 7.46. Found: C, 78.02; H, 7.67.

Example 14.—p-Carbomethoxyphenyl 2-Methyl-3-ethyl-4-phenyl-4-cyclohexenecarboxylate

This ester is prepared from the cyclohexenyl acid chloride and methyl p-hydroxybenzoate, following the procedure of Example 2. Chromatography, followed by recrystallization from ether gives the ester as white granules of m.pt. 105-106°.

$\lambda\lambda_{\text{max}}$: 5.70, 5.86, 7.78, 8.39, 8.80, 9.00, 11.79, 13.08, 13.30, 13.60, 14.27 μ .

Empirical Formula: $C_{24}H_{28}O_4$.

Calcd.: C, 76.16; H, 6.93. Found: C, 76.08; H, 6.91.

Example 15.—2-(N-Piperidino)ethyl 2-Methyl-3-ethyl-4-phenyl-4-cyclohexenecarboxylate

This ester is prepared from the cyclohexenyl acid chloride and N-(β -hydroxyethyl)piperidine, following the procedure of Example 2, but omitting acid washes which are normally used to remove pyridine. Pyridine is, in this example, removed by evaporation. Chromatography, followed by distillation, affords the ester as a yellow oil of b.pt. 165-170° at 0.001 mm.

$\lambda\lambda_{\text{max}}$: 5.78, 8.30, 8.61, 11.88, 13.20, 14.29 μ .

Empirical Formula: $C_{23}H_{33}O_2N$.

Calcd.: C, 77.70; H, 9.36. Found: C, 77.71; H, 9.10.

Example 16.—Decyl 2-Methyl-3-ethyl-4-(p-cycloptenoxy-phenyl)-3-cyclohexenecarboxylate

This ester is prepared just as described in Example 2, starting with 0.5 g. of 2-methyl-3-ethyl-4-(p-cycloptenoxyphenyl)-3-cyclohexenecarboxylic acid prepared as disclosed in U.S. Application 662,310 and n-decyl alcohol and following the same procedure of isolation, purification by chromatography and distillation. There is obtained 0.5 g. of the subject decyl ester, a viscous yellow oil which boils at 205-210° at 0.001 mm.

$\lambda\lambda_{\text{max}}$: 5.75, 8.03, 8.61, 10.05, 12.08 μ .

Empirical Formula: $C_{31}H_{48}O_3$ =469.7.

Anal.—Calcd.: C, 79.43; H, 10.32. Found: C, 79.08; H, 10.41.

Example 17.—Decyl 2-Methyl-3-ethyl-4-(p-hydroxy-phenyl)-3- and 4-cyclohexenecarboxylate

A. 1.0 g. of 2-methyl - 3 - ethyl - 4 - (p-acetoxyphenyl)-3- and 4-cyclohexenecarboxylic acid prepared as disclosed in U.S. Application No. 723,614 (mixture of isomers) is converted to the acid chloride as described in Example

75 2. The undistilled acid chloride is converted to the decyl

ester with n-decyl alcohol and purified by chromatography, as also described in Example 2, followed by distillation to give 0.6 g. of decyl 2-methyl-3-ethyl-4-(p-acetoxyphenyl)-3 and 4-cyclohexenecarboxylate:

This is a pale yellow viscous oil of b. pt. 170-180° at 0.001 mm. The NMR spectrum shows an approximate 1:1 mixture of the Δ^3 and Δ^4 isomers.

Anal.—Calcd. for $C_{28}H_{42}O_2$: C, 75.97; H, 9.56. Found: C, 75.84; H, 9.69.

B. The distilled mixture of isomers described in A (previous page) is refluxed for eight minutes in 30 ml. of methanol containing 4 ml. of water and 0.8 g. of potassium bicarbonate. The resulting clear solution is evaporated to remove methanol and the oily product is extracted with ether. The ether solution is dried and concentrated, and the residue is distilled to afford 0.5 g. of a very viscous pale yellow oil, b. pt. 185-195° at 0.001 mm. NMR shows this to be an approximate 1:1 mixture of decyl 2-methyl-3-ethyl-4-(p-hydroxyphenyl)-3-cyclohexenecarboxylate and decyl 2-methyl-3-ethyl-4-(p-hydroxyphenyl)-4-cyclohexenecarboxylate.

Empirical Formula: $C_{28}H_{40}O_3 = 400.6$.

Anal.—Calcd.: C, 77.95; H, 10.07. Found: C, 76.96; H, 10.01.

Example 18.—Decyl 2-Methyl-3-ethyl-4-(m-tolyl)-3-cyclohexenecarboxylate

A mixture of 0.5 g. of 2-methyl-3-ethyl-4-(m-tolyl)-3-cyclohexenecarboxylic acid (Example 6 of U.S. Application No. 747,075) and 5 ml. of thionyl chloride is refluxed for 15 minutes and then diluted with 10 ml. of toluene and evaporated under vacuum to a viscous oil of the acid chloride. The latter is treated with a solution of 1 ml. of decyl alcohol in 5 ml. of pyridine and this mixture is heated at 95° for 20 minutes and then diluted with hexane and washed with dilute hydrochloric acid. The hexane solution is dried and evaporated and the residual crude ester is chromatographed on alumina. Elution with benzene+hexane gives the ester, which is distilled to afford 0.4 g. of decyl 2-methyl-3-ethyl-4-(m-tolyl)-3-cyclohexenecarboxylate, a viscous pale yellow oil of b. pt. 155-160° at 0.001 mm.

$\lambda\lambda_{\text{max.}}: 5.77, 8.63, 9.94, 12.78, 14.16\mu$.

Empirical Formula: $C_{27}H_{42}O_2 = 398.6$.

Anal.—Calcd.: C, 81.35; H, 10.62. Found: C, 81.24; H, 10.75.

Example 19.—2-Methyl-2-butenyl 2-Methyl-3-ethyl-4-(p-anisyl)-3-cyclohexenecarboxylate

This ester is prepared as detailed in Example 18, starting with 0.7 g. of 2-methyl-3-ethyl-4-(p-anisyl)-3-cyclohexenecarboxylic acid (disclosed in U.S. Pat. 2,582,253) and reacting the intermediate acid chloride with tigyl alcohol (2-methyl-2-buten-1-ol). Isolation and purification are performed as described in Example 18, and the ester is distilled to afford the product as a pale yellow oil (0.55 g.) of b. pt. 145-150° at 0.001 mm.

$\lambda\lambda_{\text{max.}}: 5.75, 8.01, 8.62, 9.65, 9.98, 12.05\mu$.

Empirical Formula: $C_{22}H_{30}O_3 = 342.5$.

Anal.—Calcd.: C, 77.15; H, 8.83. Found: C, 77.33; H, 9.01.

Example 20.—2-Furylmethyl 2-Methyl-3-ethyl-4-(o-anisyl)-4-cyclohexenecarboxylate

This ester is prepared according to the procedure detailed in Example 18 starting with 0.7 g. of 2-methyl-3-ethyl-4-(o-anisyl)-4-cyclohexenecarboxylic acid prepared as disclosed in U.S. Application No. 747,075 and reacting the intermediate acid chloride with furylmethyl alcohol. Isolation and purification are performed as in Example 18, yielding a solid ester which is then recrystallized from hexane to afford the product as white prisms which melt at 81-82°. A weak hydroxyl band in the infrared spectrum, as well as the analytical values, support a formulation with partial molecule of water in the crystal.

$\lambda\lambda_{\text{max.}}: 3.15, 5.77, 8.62, 10.00, 10.27, 10.80, 11.69-11.83, 12.18, 13.04, 13.22\mu$. (KBr).

Empirical Formula: $C_{22}H_{26}O_4 \cdot \frac{1}{4}H_2O = 358.9$.

Calcd.: C, 73.62; H, 7.44. Found: C, 73.35; H, 7.33.

Example 21.—Benzyl 2-Methyl-3-ethyl-4-(p-cyclopentoxyphenyl)-3-cyclohexenecarboxylate

This ester is prepared according to the procedure detailed in Example 18, starting with 0.7 g. of 2-methyl-3-ethyl-4-(p-cyclopentoxyphenyl)-3-cyclohexenecarboxylic acid prepared as disclosed in U.S. Application No. 662,310, and reacting the intermediate acid chloride with benzyl alcohol. Isolation and purification are performed as in Example 18, and the ester is distilled to afford the product as a viscous oil (0.4 g.) of b. pt. 190-200° at 0.001 mm.

$\lambda\lambda_{\text{max.}}: 5.75, 8.03, 8.63, 9.94, 10.03, 12.07, 13.30, 13.61, 14.33\mu$.

Empirical Formula: $C_{28}H_{34}O_3 = 418.6$.

Calcd.: C, 80.34; H, 8.19. Found: C, 80.45; H, 8.34.

Example 22.—Dodecyl 2-Methyl-3-ethyl-4-(m-chlorophenyl)-4-cyclohexenecarboxylate

This ester is prepared from the cyclohexenyl acid chloride in which the 4-phenyl group is m-chloro substituted (prepared as disclosed in U.S. Application No. 747,075) and n-dodecanol, following the procedure of Example 2. Chromatography on alumina affords the crude ester free of the fatty alcohol and distillation gives the ester as a colorless oil of b.pt. 195-200°/0.001 mm.

$\lambda\lambda_{\text{max.}}: 5.78, 8.60, 10.01, 11.31, 11.88, 12.78, 13.70, 14.33\mu$.

Empirical Formula: $C_{28}H_{43}O_2Cl$.

Calcd.: C, 75.21; H, 9.69. Found: C, 75.28; H, 9.63.

Example 23.—Decyl 2-Methyl-3-ethyl-4-(p-acetoxyphenyl)-3-cyclohexenecarboxylate

The crude acid chloride is prepared as described in Example 2 from 0.6 g. of 2-methyl-3-ethyl-4-(p-acetoxyphenyl)-3-cyclohexenecarboxylic acid (prepared as disclosed in U.S. Application No. 723,614) and 5 ml. of thionyl chloride (this follows the general procedure). This crude acid chloride is then reacted with decyl alcohol in pyridine again following the procedure of Example 2. Chromatography on alumina affords crude ester and distillation gives the desired ester as a pale yellow oil of b. pt. 180-190°/0.001 mm.

$\lambda\lambda_{\text{max.}}: 5.67, 5.78, 8.33, 8.60, 9.82, 10.97, 11.80, 12.52\mu$.

Empirical Formula: $C_{28}H_{42}O_4 = 442.6$.

Calcd.: C, 75.97; H, 9.56. Found: C, 75.84; H, 9.69.

Example 24.— β -Methoxyethyl 2-Methyl-3-ethyl-4-phenyl-4-cyclohexenecarboxylate

This ester is prepared from the Δ^4 -cyclohexenyl acid chloride and ethylene glycol monomethyl ester, following the procedure of Example 2 Chromatography on alumina

affords crude ester and distillation gives the desired ester as a pale yellow oil of b. pt. 130-135°/0.001 mm.

$\lambda\lambda$ max.: 5.78, 8.30, 8.60, 8.81, 9.57, 11.57 11.88, 13.22, 14.25 μ .

Empirical Formula: $C_{15}H_{26}O_3$ = 302.4.

Calcd.: C, 75.46; H, 8.67. Found: C, 75.40; H, 8.50.

Example 25.—Carbethoxymethyl 2-Methyl-3-ethyl-4-phenyl-4-cyclohexenecarboxylate

This ester is prepared from the Δ^4 -cyclohexenyl acid chloride and ethyl glycolate, following the procedure of Example 2. Chromatography on alumina affords crude ester and distillation gives the desired ester as a colorless oil of b. pt. 150-155°/0.001 mm.

$\lambda\lambda$ max.: 5.68, 5.73, 8.19, 8.34, 8.68, 9.20, 9.31, 9.70, 10.80, 11.80, 13.20, 14.24 μ .

Empirical Formula: $C_{20}H_{26}O_4$ = 330.4.

Calcd.: C, 72.70; H, 7.93. Found: C, 72.77; H, 8.09.

While the preparation of only some of the compounds of this invention have been specifically described, one skilled in the art should be able to prepare the remainder of the compounds following the general techniques set forth.

As mentioned previously, the compounds of this invention exhibit anti-littering effects when given orally or parenterally and are estrogenic agents to varying degrees.

Estrogenic effects are measured against the estrogenic effects of estradiol as a standard. In carrying out the test, female rats of Wistar-derived strain are bilaterally ovariectomized under light ether anesthesia. About a week following surgery all animals are given a priming dose of 2-10 μ g. estradiol-17 β by subcutaneous injection and vaginal smears are taken on each of the next two days. Animals which do not show vaginal cornification are rested a week and reprimed. Rats which respond positively to the priming injection are rested a week and then given a single subcutaneous injection of the test material in sesame oil. Vaginal smears are taken daily to assess the duration of estrogenic response (vaginal cornification) in each animal as opposed to the vaginal cornification induced by the priming. The results, tabulated in Table I, for certain of the compounds prepared according to the examples hereinbefore set out show that the compounds of this invention have substantial estrogenic activity.

The parenteral anti-littering properties of the compounds are measured by administering to adult female rats of Wistar-derived strain a single subcutaneous injection of the test material in sesame oil. Controls receive

sesame oil vehicle only. Ordinarily twenty animals are assigned to each group.

Both groups are cohabitated with adult male rats in the ratio of 3 males per females starting on the day of treatment. Rats are examined twice weekly for gross signs of pregnancy. Gravid animals are removed and allowed to deliver so that a count of young and their condition may be recorded. The mean interval between drug administration (and cohabitation) and conception is calculated for each group using an average gestation length of 21 days.

Cohabitation is continued for 90 days or until 80% of the females become pregnant, whichever occurs sooner.

The minimum dosage in mg./kg. body weight required to prevent littering in the rats for various compounds, the preparation of which was specifically described in the examples, is set out in Table I. The actual effect of some of the compounds on littering at various dosage levels is set out in Table II.

While the determination of the antilittering effect of a compound is important in that it shows whether or not a compound will suppress reproduction, it does not pinpoint the precise manner in which reproduction is suppressed. It has been determined that the compounds of the invention are also antizygotic agents. A zygote is the fertilized ovum, and an antizygotic agent is one which destroys the zygote prior to implantation in the uterus. One specific form of zygote destruction is the lysing of the zygote.

In order to determine whether or not a compound is antizygotic, adult male and female rats are cohabitated until sperm is found in the vagina. Following the presence of sperm, the female rats are dosed on two successive days with the compound, and on the ninth day after the presence of sperm is noted, the rats are autopsied and the uteri are examined for the presence of conceptuses. Lack of conceptuses indicates antizygotic effect. A control group of rats is similarly treated except that there is no dosing with the compound under test.

Table I tabulates (for certain compounds) the minimum effective dosage of said compounds needed to obtain an antizygotic effect.

TABLE I

R	R'	Pharmacological activity ²			
		Anti- Δ - zygotic ³	Estrogenic ⁴	Antilittering	
		Oral ⁵	Parenteral ⁶		
Example: ¹					
1.....	H	-CH ₂ CHOHCH ₂ OH	4 10 μ g.	2 $\times$ EE	10 μ g. Inact. 5 mg.
2.....	H		4 500 μ g.	$\frac{1}{100}$ $\times$ EE	500 μ g. 50 mg. (S-C)
3.....	H	-CH(C ₆ H ₅) ₂	4 20 μ g.	2/5 $\times$ EE	25 μ g. >2.5 mg.
4.....	H		4	2 $\times$ EE	5 μ g. 1.0 mg.
5.....	H	-C ₁₀ H ₂₁	4	1/2 $\times$ EE	25 μ g. >1.0 mg.

Octyl 1-carboxylate		5.0 (IG)	-----	4/10	-----	22.2
		10.0	-----	6/10	-----	22.8
		25.0	-----	3/10	-----	21.3

¹ No pregnancies.

From Table I it can be seen that the alkenyl esters (Examples 11 and 12) and the cyclopentyl ester (Example 4) are active when administered parenterally or orally in small doses compared to the octyl and hexyl esters of U.S. Pat. 3,344,147. The secondary alkyl esters (Example 10) have high oral activity despite very low estrogenicity. The 1-adamantyl esters (Example 2) also exhibit oral and parenteral activity despite very low estrogenicity.

From Table II it can be seen that the 2-adamantyl esters (Example 7) have long acting effects when administered orally or parenterally compared with the octyl ester of U.S. Pat. 3,344,147.

What is claimed is:

1. 2-Nonadecyl 2-methyl-3-ethyl-4-phenyl-4-cyclohexenecarboxylate.

2. 2-Methyl-2-butenyl 2-methyl-3-ethyl-4-phenyl-3-cyclohexenecarboxylate.

3. 2-Methyl-2-butenyl 2-methyl-3-ethyl-4-phenyl-4-cyclohexenecarboxylate.
